ADJUSTABLE SPRING CURTAIN ROD

Charles W. Gould, Philadelphia, Pa.

Application October 23, 1935, Serial No. 46,243

5 Claims. (Cl. 156—19)

My invention relates to a new and useful adjustable spring curtain rod, and has particular reference to rods used for hanging different kinds of draperies at windows, doors and the like.

5 One of the objects of the invention is to provide unique means for making spring operated rods adjustable to various lengths so that they may be mounted in different width window and door frames.

10 Another object of the invention is to construct a curtain rod of a number of telescoping sections, at least one of which is urged outwardly by a spring and another is limited to any one of a plurality of predetermined positions.

15 Another object of the invention is to provide a curtain rod of this class with an adjustable stop which will limit the inward sliding action of one section relative to another section beyond changeable predetermined positions so that in effect the rod is maintained in any adjustment.

20 Another object of this invention is to produce an adjustable stop of unique construction for use with a telescoping sectional curtain rod.

A still further object of the present invention is the provision of an adjustable spring curtain rod comprising a center section, a permanently attached or captive spring pressed end section slidably mounted on one end of the center section, another end section telescopically mounted on the opposite end of said center section to limit the inward sliding movement of said other end section relative to the center section.

With the above and other objects in view, this invention consists of the details of construction hereinafter set forth and then specifically designated by the claims.

In order that those skilled in the art to which this invention appertains may understand how to make and use the same I will describe its construction in detail, referring by numerals to the accompanying drawing forming a part of this application, in which;

Fig. 1 is an elevation of the complete rod.

Fig. 2 is a slightly enlarged longitudinal sectional view thereof.

Fig. 3 is a further enlarged fragmentary longitudinal sectional view to illustrate the adjustable stop which is shown in its unlocked or open position and without the adjusting end section.

50 Fig. 4 is a similar view showing the stop in its closed or locked position and with the adjusting end section in place.

Fig. 5 is a fragmentary view, partly in elevation and partly in section and at right angles to Figs. 3 and 4.

Fig. 6 is a perspective view of the adjustable stop, and

Fig. 7 is an enlarged fragmentary sectional view of the adjusting end member and the contiguous end of the center section to illustrate the manner of removably connecting an attaching member, here shown as a vacuum cup.

In carrying out my invention as herein embodied 10 represents a tubular center section having a row of longitudinally spaced holes 11 10 adjacent one end and a pair of oppositely positioned longitudinal slots 12 adjacent the other end. The end of the center section, near which the holes 11 are located, is internally threaded as at 13 to receive the secured threaded shank 14 15 of the attaching member 15 which engages a face of a window or door frame or other support and said attaching member is here shown as a vacuum cup. Preferably the threaded end of said center member is reduced in size as 20 plainly shown in Fig. 7.

The spring actuated end section 16 telescopes on the slotted portion of the center section so as to slide longitudinally and has a rivet 17 fixed in the walls of said spring actuated end section 25 16 projecting across its interior and through the slots in the center section. This rivet permanently or captively connects the spring actuated end section to the center section and prevents them from rotating or being separated 30 while allowing for a limited longitudinal telescoping or sliding movement. A spring 18 is positioned within said spring actuated end section between the outer end thereof and the adjacent end of the center section so as to normally urge said spring actuated end section outward. The inner end of the section 16 may have a ferrule 19 thereon.

The outer end of said spring actuated end section 16 is internally threaded to receive the 40 threaded shank 14 of an attaching member 15 the same as previously described, and said outer end of said spring actuated end section is preferably reduced in diameter as shown so that the attaching members will be interchangeable. 45

An adjusting end section 20 is telescopically mounted on the perforated portion of the center section 10 for longitudinal adjustment and is free to be removed from said center section. The outer end of said adjusting end section 20 is internally threaded to receive the threaded shank 50 of an attaching member 15 and said outer end is preferably reduced in diameter so as to be the same size as the reduced ends of the center and spring actuated end sections.

In order to limit the inward movement of the adjusting end section 20 and thereby provide for regulating the length of the curtain rod, an adjustable stop 21 is mounted on the center section 10 to be engaged by the inner end of said section 20. This stop includes a cylinder 22 provided with a resilient catch 23, the nose of which is adapted to be projected into any one of the holes 11. Preferably the catch is produced from a portion of the cylinder by partially cutting out a suitable area and then fashioning the same so that it normally lies outside of the outer circumference of balance of the cylinder and has an inwardly projecting nose on the free end.

15 The catch is forced inward to cause the nose to enter a hole 11 by a sleeve 24 which slides over the cylinder and because of the fairly snug fitting arrangement the catch will be substantially fully depressed.

20 Assuming that the assembled rod as illustrated in Figs. 1 and 2 is for use in a thirty inch window frame then the actual length over all should be more than thirty inches, for example it should be thirty-one or thirty-two inches in length from the tip of one attaching member to the tip of the other attaching member. By grasping the two end sections and forcing them toward each other, the spring actuated end section will be slid over the center section against the action of the 30 spring until the length of the rod is temporarily less than thirty inches. The rod may then be placed in the window frame and released at which time the spring will urge the rod sections apart so that said rod will be firmly supported in the 35 window frame.

If it is desired that the rod be used in a wider window frame, then the adjusting end section 20 is moved outward and the sleeve 24 is withdrawn from the cylinder which will release the 40 catch and permit it to spring outward as illustrated in Fig. 3. With the adjustable stop in this open or unlocked condition the parts may be moved along the center rod section until the nose of the catch will register with another of the holes 11 after which the sleeve is replaced on the cylinder so as to depress the catch and cause its nose to enter said other hole thereby closing or locking the stop as shown in Fig. 4. The adjusting end section is now moved inward 45 until its inner end engages the stop at which time the rod is ready for use in the wider window frame.

Should it be desirable to use the rod in a window frame which is narrower than the shortest 50 length of the completely assembled rod, the adjusting end section may be discarded and the attaching member removed therefrom and connected to the threaded end of the center section.

Of course I do not wish to be limited to the 55 exact details of construction herein shown and described as these may be varied without departing from the spirit of my invention.

Having thus fully described my invention, what I claim as new and useful is:—

60 1. An adjustable spring curtain rod comprising a center section, end sections telescopically mounted on the ends of said center section, a spring to urge one of said end sections outward, and means adjustably mounted on the center 65 section to be engaged by the other end section to limit the inward movement of said other end section a predetermined distance.

2. An adjustable spring curtain rod comprising a tubular center section having opposed longitudinal slots adjacent one end thereof, an end section telescoping over said slotted portion of the center section, means fixed to said end section and projecting through the slots in the center section to limit longitudinal movement of said end section relative to the center section, a spring to urge said end section outward, another end section telescoping over the other portion of the center section, and means adjustably mounted on the center section to be engaged by said other end section to maintain the latter in any selected predetermined position.

3. The structure in claim 2 wherein the outer 15 ends of both end sections and one end of the center section are all internally threaded alike, in combination with attaching members having screw threaded shanks for interchangeable connection with the threaded ends of the several 20 sections.

4. In a device of the kind described, a center rod section having a row of longitudinally spaced holes adjacent one end, an adjusting end section slidably mounted on the perforated portion 25 of said center section and free to move back and forth, an adjustable stop slidably mounted on the center section and provided with means to register with any one of the holes for selectively positioning said stop which is to be engaged by 30 the inner end of the adjusting end section to limit the inward movement of the latter beyond a selected predetermined location, and a spring actuated end section on the opposite end of said center section.

5. A rod of the class described comprising a center section having opposed longitudinal slots adjacent one end and a row of longitudinally spaced holes adjacent the other end and said other end being reduced in diameter and internally threaded, a stop including a cylindrical body slidably mounted on said center section, a resilient catch carried by said body and having a nose for registration with any one of said holes and a sleeve telescoping over the body to depress the catch for projecting the nose of said catch into a hole and thereby holding the stop in any preselected position, an adjusting end section slidably mounted on the perforated portion of the center section and engaging the stop 50 to determine the adjustment of said adjusting end section, the outer end of said adjusting end section being reduced in diameter and internally threaded the same as the similar end of the center section, another end section slidably mounted 55 on the slotted end of the center section and having its outer end reduced in diameter and internally threaded the same as the outer end of the adjusting end section, a rivet mounted in the walls of the said other end section and projecting through both of the slots in the center section to limit the sliding movements of said other end section and said center section relative to each other, a spring within said other end section and engaging a portion thereof and the 60 adjacent end of the center section to urge said other end section outward, vacuum cups, and threaded shanks on said cups for interchangeable connection with the internally threaded reduced ends of the several sections.
